TELEPHONE SWITCHBOARD TURRET

Alton M. Hambric, Birmingham, Ala., assignor to North American Telephone Corporation

Filed Apr. 6, 1972, Ser. No. 241,886

Claims priority, application Japan Oct. 20, 1971

Term of patent 14 years

Int. Cl. D14—03

U.S. Cl. D26—14 A

FIG 1

FIG. 3

FIG. 2

FIG. 1 is a perspective view of a telephone switchboard turret showing my new design;

FIG. 2 is a side elevational view thereof showing the side opposite the side shown in FIG. 1; and

FIG. 3 is a rear elevational view thereof.

I claim:

The ornamental design for a telephone switchboard turret, as shown.
